BABY CARRIAGE

Donald B. Cerf, 309 E. Live Oak, San Gabriel, Calif.

Filed May 10, 1965, Ser. No. 85,194

Term of patent 3½ years

(Cl. D14—14)

FIG. 1 is a front perspective view of my design for a baby carriage;

FIG. 2 is a side view of my design for a baby carriage; and

FIG. 3 is a front elevational view of my design for a baby carriage.

The rear not shown is substantially plain and the side not shown is a mirror image of the side shown.

I claim:

The ornamental design for a baby carriage, substantially as shown and described.
